UNITED STATES PATENT OFFICE.

GEORGE WASHINGTON GRISWOLD, OF POTTERSVILLE, NEW YORK.

IMPROVEMENT IN SAW-GUMMERS.

Specification forming part of Letters Patent No. **159,318**, dated February 2, 1875; application filed November 30, 1874.

To all whom it may concern:

Be it known that I, GEORGE W. GRISWOLD, of Pottersville, in the county of Warren and State of New York, have invented a new and useful Improvement in Saw - Gummers, of which the following is a specification:

The object of this invention is to improve the present machines used for gumming saws; and it consists in the arrangement of the cutters of an apparatus for cutting between the teeth or gumming, constructed substantially as hereinafter described.

In the accompanying drawing, Figure 1 is a side view, showing the cutting - cylinder in cross-section. Fig. 2 is a top view of the entire machine, the saw being seen in both figures in dotted lines and the bow cut off.

Similar letters of reference indicate corresponding parts.

A represents a handle, to which the clamping device and the cutting-cylinder are attached. B B are the clamps for holding the saw. These clamping-disks are on the ends of the screws C and D, the latter of which passes through the end of the handle, and the other through the end of the bow E. The other end of the bow E is confined on the outside of the handle by the nut F. G G are levers in the heads for turning the screws. The

bow E rises up from the screws, as seen in Fig. 1, to give room for the saw, as indicated in Fig. 1. H is the saw. I is a hollow sleeve, attached to the side of the handle. J is the cutting-cylinder. This cylinder is made with a shank, which passes through the sleeve. It is held in position by the shoulder K and by the crank L, as seen in Fig. 2. The cylinder is made hollow, and has one or more slots through its surface. M M are cutters, passed through the slots, which are inserted from the end, and which are beveled at the inner ends, so that they correspond with the surface of the cylinder. The cutters cross each other, and are fastened by the set-screws N N. Their edges project sufficiently to take a thin chip from the saw as the cylinder or cutter-head revolves.

Having thus described my invention, I claim as new and desire to secure by Letters Patent—

The combination of the cutters M M and cylinder J, constructed and arranged substantially as shown and described, for the purposes set forth.

GEORGE WASHINGTON GRISWOLD.
